UNITED STATES PATENT OFFICE.

LEONARD MARCUS JONES, OF DULWICH, ENGLAND.

SYRINGE.

Application filed August 1, 1923. Serial No. 655,070.

To all whom it may concern:

Be it known that I, LEONARD MARCUS JONES, a British subject, residing at 22 Court Lane Gardens, Dulwich, in the county of 5 London, England, have invented certain new and useful Improvements in Syringes, of which the following is a specification.

This invention relates to syringes, and more particularly to fire extinguishers of the 10 kind wherein a piston is employed to eject the fluid. As hitherto constructed such appliances suffer from the defect that when stored ready for use the fluid content leaks out through the nozzle, and the present invention has for its object to provide an 15 appliance of the type described wherein the above objection is overcome.

A further object of the invention is to provide within the syringe a device operating 20 as a closure for the inner end of the outlet tube when the syringe is stored ready for use, but adapted to be released from or moved out of the closing position when the 25 syringe is required to operate. A further object of the invention is to operate said leak closing device through the medium of an elastic link and to house said device in a housing contained in an air pressure chamber and a further object is to situate said 30 chamber at the forward end of the syringe.

A further object is to render said device 35 easily accessible on the removal of the nozzle. In the preferred form, the said closure is maintained in its operative closing position by means of the depressed piston. In this connection it is known in fire extinguishers of the type described to provide that the piston is fully depressed when the device is being stored, and is caused to engage 40 with a part of the casing so as to remain depressed until released from such engagement when the extinguisher is required for use.

In the drawings:

45 Fig. 1 is a sectional view of the improved syringe.

Fig. 2 is an enlarged sectional view of the delivery end of such syringe.

In the drawings, the syringe illustrated, 50 comprises an outer casing 20, divided by a partition 21 into two chambers, namely a liquid chamber 22, and an air cushion chamber 23, the latter being positioned at the delivery end of the syringe. A cylindrical 55 housing 1 passes axially through the casing and serves as a pump chamber in which the

piston 2 reciprocates. The piston rod emerges from the casing to a fitting 26 comprising an annular passage 27 leading to an enlarged chamber 28. The side walls of the passage 27 are provided with two slots 29 in which are adapted to enter lugs 30 formed on the handle of the piston rod, so that the latter can be pushed to the full extent of its stroke and rotated, whereupon the lugs 30 will be held within the chamber 28 and the piston be prevented from rising. In use, on the operation of the piston 2, liquid is drawn through one of the gratings 31, 32, according to the inclination of the syringe, and delivered by 70 the pump through the pipe 33 into the air cushion chamber 23, whence it passes through the sieve 25 and tube 24 to the nozzle. The syringe is operated with the tube 24 directly downwardly, and owing to the 75 provision of a cushion of air in the chamber 23, the liquid is delivered from the nozzle in a constant flow.

Referring now particularly to Fig. 2 of the drawing, the tubular housing 1 in which the piston 2 is adapted to reciprocate is closed intermediate its length by a holed plug 3 and at the bottom by a removable plug constituting the nozzle 4. Between 80 said plug and said nozzle the housing 1 encloses a chamber 5 through which the fluid contents of the extinguisher are required to pass to the outlet of the nozzle 4.

Within the said chamber, I provide a closing device forming the object of this invention which preferably comprises two separate parts 6^a, 6^b. The first part comprises a cylindrical body 7 having its outer end, that is, the end directed towards the nozzle, enlarged to form a hollow cylinder 8 of which 90 the neck is externally shaped to the form of a cone or of a truncated cone 8^a adapted to engage in a similarly-shaped face 3^a in the corresponding wall of the plug. The inner end of the portion 7 is adapted to be 100 engaged and depressed by the piston 2 when the latter is depressed below the position shown; but the piston is illustrated as at the bottom of its normal stroke and is only intended to be further depressed during storage.

Within the said cylinder 8 is adapted to slide an enlargement 9 formed on the inner end of the member 6^b, the parts 8, 9 being urged apart by a spring 10. The outer end 11 of the part 6^b slides within the central passage 12 of the nozzle 4, making a liquid-

tight joint therewith. The said outer end 11 is recessed, and the wall of the recess is pierced by holes 13 so as to give access to the chamber 5 when the parts are in the position shown. The part 8 of the anti-leak device is urged inwardly from the nozzle 4 by means of a spring 14 which abuts against said nozzle and against the end face of the part 8 which is fitted with a threaded flanged collar 17 to provide an adequate bearing surface, the cylindrical member 9 serving as a guide for the spring 14 and being flanged as shown at 18 so as to be withdrawn away from the nozzle 4 by the flange of the part 17 when the latter is lifted by the spring 14. It is to be noted that the inner edge of the central recess 12 of the nozzle 14 is cut away to form a conical seating 15 with which a conical face 16 formed on the part 6^b is adapted to engage. When the nozzle 4 is unscrewed, all the parts within the chamber 5 can be withdrawn if desired for refitting or repair.

The chamber 5 is situated within the pressure chamber 23 and access is given thereto by a radial tube 24 terminating in a filter 25.

In use liquid is fed to the pressure chamber on both strokes of the piston 2 through the tube 26 leading from the chamber 22. The said liquid falls to the bottom of the chamber 23, it being understood that the syringe is used in a position such that the tube 24 is directed downwardly.

In these circumstances, owing to the pressure of the air cushion in the chamber 23, a continuous pressure is maintained tending to drive the liquid up the tube 24.

When the parts are in the position shown, the liquid passing up the tube 24 has free egress out of the chamber 5 through the holes 13 and passage 12 of the nozzle 4, and it is to be understood that unless depressed by the piston the parts are maintained in the position shown by the spring 14 leak from the pump chamber to the chamber 5 being effectively prevented by the conical faces 3^a, 8^a, controlled by the spring 14.

When the syringe is intended to be stored the piston is depressed below the position shown and engages with the part 7, depressing the latter and causing the part 11 through the intermediary of the spring 10 to be forced downwardly until the face 16 firmly engages against the seating 15. In this position the holes 13 have entered the passage in the nozzle 4, and the chamber 5 is maintained closed against leak. Further, the engaging conical faces 16, 15, effectively close the passage 12 against liquid escaping past the wall of the part 11. As stated, the piston is adapted to be held in the said closing position by any known means. Owing to the provision of the spring 10 actuating the closing element 11, the device includes an elastic link which ensures proper closure

of the nozzle in case the length of the piston rod is a little over or under the designed length when held down by the locking device.

I claim:—

1. A syringe, comprising a casing, a partition extending transverse the casing and dividing the casing into a liquid chamber and an air cushion chamber, each of the full sectional area of the casing, a housing extending lengthwise the casing and through both chambers, a piston reciprocal in the housing, a nozzle carried by the housing, and means operable in the housing to control communication between the air chamber and said nozzle in accordance with the position of the piston. 70

2. A syringe, comprising a casing, a partition extending transverse the casing and dividing the casing into a liquid chamber 85 and an air cushion chamber, each of the full sectional area of the casing, a housing extending lengthwise the casing and through both chambers a piston reciprocal in the housing, a nozzle carried by the housing, 90 and means operable in the housing to control communication between the air chamber and said nozzle in accordance with the position of the piston, said means serving when the piston is fully depressed to close communication 95 between the air cushion chamber and the nozzle.

3. In a syringe, a casing, a pump housing extending throughout the length of the casing, a delivery nozzle carried by the housing and projecting beyond the casing, a partition arranged in the casing and encircling the housing to divide the casing into a liquid chamber and an air cushion chamber, each surrounding the housing and of the full transverse dimension of the casing, a piston operable in the housing to deliver fluid from the liquid chamber to the air cushion chamber, a communication between the air cushion chamber and the housing, and valve mechanism normally permitting communication between the housing and nozzle in the operative positions of the piston, said valve mechanism being operable by the piston in one position of the latter to cut off communication between the housing and nozzle. 100

4. In a syringe, a casing, a pump housing extending throughout the length of the casing, a delivery nozzle carried by the housing and projecting beyond the casing, a partition arranged in the casing and encircling the housing to divide the casing into a liquid chamber and an air cushion chamber, each surrounding the housing and of the full transverse dimension of the casing, a piston operable in the housing to deliver fluid from the liquid chamber to the air cushion chamber, a communication between the air cushion chamber and the housing, a plunger operable in the nozzle and adapted 110

in one position to establish communication between the housing and nozzle and adapted in another position to cut off said communication, means for holding the plunger in position to establish said communication in the pumping operations of the piston, and means operable by the piston in a predetermined position to actuate the plunger to cut off said communication between the nozzle and housing.

5. In a syringe, a casing, a pump housing extending throughout the length of the casing, a delivery nozzle carried by the housing and projecting beyond the casing, a partition arranged in the casing and encircling the housing to divide the casing into a liquid chamber and an air cushion chamber, each surrounding the housing and of the full transverse dimension of the casing, a piston

operable in the housing to deliver fluid from the liquid chamber to the air cushion chamber, a communication between the air cushion chamber and the housing, a plunger operable in the nozzle and adapted in one position to establish communication between the housing and nozzle and adapted in another position to cut off said communication, a spring for normally holding the plunger in position to establish communication between the nozzle and housing in the pumping operations of the piston, and a member to be operated by the piston in a predetermined position of the latter to move the plunger to cut off communication between the housing and nozzle.

In testimony whereof I affix my signature.

LEONARD M. JONES.
